UNITED STATES PATENT OFFICE.

RICHARD CLAYTON FRASER, OF CENTRAL CITY, COLORADO, ASSIGNOR OF ONE-THIRD
TO W. R. FRASER, OF DURANGO, COLORADO.

PNEUMATIC OR STEAM DRILL.

1,210,299.

Specification of Letters Patent. Patented Dec. 26, 1916.

Application filed August 20, 1914. Serial No. 857,639.

To all whom it may concern:

Be it known that I, RICHARD C. FRASER, a citizen of the United States, residing at Central City, in the county of Gilpin and State of Colorado, have invented a new and useful Pneumatic or Steam Drill or Hammer; and I do hereby declare the following to be a full, clear, and exact description of the invention, such as will enable others skilled in the art to which it appertains to make and use the same.

This invention relates to a pneumatic, steam drill or hammer, for drilling rocks and the like.

As one of the objects of the invention is the provision of an improved construction of drill including a pneumatic or steam piston and provided with a rear yieldably mounted head, which relieves the piston and the entire device of the shock and jar incident to the blow of the drill tool.

The invention aims as another object to provide a piston rod rifled, so as to impart a partial rotary movement to the piston as it is driven outwardly, there being a ratchet mechanism to prevent the retrogression of the piston in a rotary direction when receding. In this manner the piston receives an intermittent rotary movement.

Another object of the invention is the provision of a forward yieldable head of the piston cylinder, acting to give or yield as the piston recedes or moves forwardly.

A further object of the invention is the provision of means for projecting water or the like through the piston, and into the hole which is being drilled.

In practical fields the details of construction may be subjected to alterations, falling within the scope of what is claimed.

The invention comprises further features and combination of parts, as hereinafter set forth, shown in the drawings and claimed.

In the drawings:—Figure 1 is a view in perspective of the improved drill mechanism constructed in accordance with the invention. Fig. 2 is a longitudinal sectional view. Fig. 3 is a horizontal sectional view on line 3—3 of Fig. 2. Fig. 4 is a transverse sectional view on line 4—4 of Fig. 2. Fig. 5 is a longitudinal sectional view through the steam or air chest, showing the auxiliary valve in another position than that shown in Fig. 2. Fig. 6 is a horizontal sectional view through the steam or air chest, showing how

the steam or air passes through the auxiliary valve into the cylinder. Fig. 7 is a detail view of the auxiliary valve. Fig. 6^a is a sectional view on line 6^a—6^a of Fig. 4. Fig. 8 is an enlarged detail sectional view through the parts 28, 30 and 31.

Referring more especially to the drawings, 1 designates a base member, which may be supported in any suitable manner, and is provided with an elongated trough 65 device or plate 2 constructed with guides 3, in which the flanges 4 of the cylinder 5 are guided. Extending through the elongated trough plate, that is, through the ribs 7 at the ends thereof are rods 8 having nuts 9 70 at the ends 10. On the other end portions of the rods tubes 11 are telescopically arranged, there being washers between the tubes and one end of the elongated plate. The end portions 13 of the rods 8 extend 75 through the cross heads 14 having nuts 15, there being washers 16 between the cross-head and the tubes 11. Mounted in a bearing 17 in the crosshead swivelly is a rod 18 having a thread 19 upon its end 20 beyond 80 the crosshead. These threads 19 terminate in a shoulder 21, between which and the crank a washer 22 is arranged. The crank is rotated or threaded as shown at 23 to engage the thread 19 and is adjusted jam 85 against the washer 22. The said threads 19 extend in a direction, so that when the crank is rotated in the proper direction to feed the cylinder forward, the tighter the crank 24 is arranged against the washer. To further lock the crank on the threaded end 19, the same is split as shown at 25, and a screw bolt extends through the split end, and by tightening up the nut thereon, the split portions are drawn close together. The rod 18 90 has an integral collar 27 between which and the washer 22 the crosshead 14 is arranged. 95

A sleeve 28 is threaded upon the rod 18 as shown. This sleeve is mounted in a projection of the lower portion of the cylinder, there being lock nuts 29 and 30 on each end of the sleeve to hold the sleeve in the projection 31. When the rod 18 is rotated by the crank, the cylinder and its attending parts are adjusted forwardly or rearwardly. The 100 cylinder 5 has the usual piston 32 mounted in its chamber 5^a, and which piston 32 is provided with a piston rod 33, through which and the piston a bore 34 extends. One end 35 of the cylinder has a head 36 provided 105

110

with a reduced portion 37 extending into the bore of the cylinder. A tube 38 having an integral collar 39 is provided. The end 40 of the tube 38 beyond the collar 39 extends partially through the head and has a ringed nut 41 threaded thereto, thereby holding the tube 38 in place. The end portion 40 of said tube opens into an interiorly threaded cavity 42 of the head, and engaging the threads of said cavity is the usual plug 43. A passage 45 is formed laterally in the head 36, and this passage opens into the cavity, and one end of the passage is threaded to receive suitable connections from a water supply (not shown). The tube 38 telescopes the bore of the piston, in such wise as to prevent the water (which passes through the tube, the piston and the piston rod, so as to reach the bore of the drilling tool, so as to enter the hole which is being drilled) from entering the piston chamber 5^a of the cylinder 5. The plug 43 is utilized for the purpose of cutting off a supply of water through the tube and the piston rod 2^a and piston, which water is used for cooling and washing out the hole that is being drilled. By entirely removing the plug, and closing a valve 48 in said connections of said passage (which connections are designated by the number 49) the excess water may be removed from the passage through the tube 38, the piston and the piston rod. The other end 50 of said cylinder is provided with a dominant cylinder head 51 having a reduced portion 52, which fits the interior of the end 50 of the cylinder. An auxiliary cylinder head 53 is provided, and is supplied with a slight reduced extension 54, which fits an annular recess 55 of the dominant cylinder head. The head 36, the dominant head 51 and the auxiliary head 53 are all provided with lateral projections or ears 56, through which the rods 57 extend. These rods 57 are provided with heads 58, which engage the ears 56 of the head 36. The ends 59 of the rods 57 are threaded, to receive the nuts 60, between which and the ears 56 of the auxiliary head 53, coil springs 61 are interposed. In this manner the heads are yieldably held 50 in place, and are allowed to give or yield incident to the movement of the piston, thereby slightly opening the opposite ends of the cylinder, thereby affording cushioning ports. The opposite sides of the cylinder at each end are provided with ears 62, through which the rods 57 extend.

The piston 32 is constructed with the usual packing rings 63, and it will be observed that the piston 32 is detachably connected to the piston rod, by means of a plug or pin 64, threaded in place as shown.

The dominant cylinder head 51 has a cavity 65, in which a ratchet collar 66 is arranged, the teeth of which are engaged by the spring retained pawls 67, which are lo-

cated or mounted in recesses 68 of the head 51. The ratchet collar upon its circular opening has oppositely arranged lugs 68^a, which extend into the rifled grooves 69 of the piston rod 33. The grooves 69 are disposed slightly spirally or at an angle to the rod, so that when the piston is driven forwardly a partially rotary movement is imparted thereto, but upon the rearward movement of the piston and the rod the ratchet collar slips by the spring pawls which will permit the piston rod to gain another position, in order to receive a further partial revoluble movement, when again being driven forward. It will be seen that by this arrangement the piston rod and the tool 85 at its end will receive an intermittent rotary motion. The auxiliary cylinder head is provided with a suitable packing ring 70, held in place by a jam collar 71, which is threaded upon a reduced extension 72 of the auxiliary cylinder head, there being a spring tensioned pin mounted in a cavity of the head 53, which cavity and spring tensioned pin are designated by the numerals 73 and 74. The piston rod 33 is provided with an extension 35 threaded into a tool holding head 76, there being a set screw 77 to secure the head 76 against movement. The head 76 is provided with a bore registering with the bore 78 in the piston rod, and this bore 78 of the head 76 is designed for the reception of the drill tool 85, which is held or clamped into position by the tongue 80 of the clamping block 81, which is secured in place by the transversely disposed staple 82, which extends through the head 76 and provided with suitable nuts, by which the staple is held firmly in the recess 83 of the block 81. The tongue 80 of the block 81 extends in a slot 84 in the head 76 and engages a flat portion 85 of the drill tool, thereby preventing movement of the drill tool relative to the head 76.

Bolted upon a flat surface of the cylinder is the steam or air chest casing 87, which is provided with an inlet port 88, into which the steam or air pipe 89 (which receives its supply from any suitable source, not shown) extends. The port 88 opens into a chamber 90, which is in communication with the auxiliary valve chamber 91, by virtue of the ports 92 and 93. Passages 94 and 95 extend from the interior of the cylinder at each end, partially longitudinally of the cylinder and through the wall thereof and through the under portion of the steam or air chest and open into the auxiliary valve chamber. The portions of the passages 94 and 95 which pass through the wall of the chest are designated by the numerals 94^a and 95^a. Extending from the auxiliary valve chamber 91 is a port or passage 96 between the ports 94^a and 95^a, which port 96 or passage passes through a portion of the cylinder and has an exhaust pipe or conduit 97 connected 130

thereto. Also communicating between the interior of the cylinder 5 and the auxiliary valve chamber 91 are ports 98 and 99, which constitute means for the passage of air or steam from the interior of the cylinder to the chamber 91, for not only actuating the auxiliary valve 100, but for cushioning the piston.

The auxiliary valve 100 is cylindrical in shape, and is provided with a flat surface 101, which is engaged by a plug which extends through the upper wall of the chest and designated by the numeral 102. Passages 103 and 104 terminating in the ports 105, 106, 107 and 108 extend through the auxiliary valve, there being additional passages 109 and 110 communicating with said passages 103 and 104.

Supposing the valve 100 to be in such position that the port of the passage 110 is in communication with the port 93 of the chamber 90, in which case the port 107 is in communication with the port 95^a of the passage 95, and the piston is adjacent the end 50 of the cylinder. In this case steam or air from the chamber 90 will pass through the port 93 through the passage 110, through the passage 104, down through the passage 95, acting upon the piston in such wise as to drive the piston rearwardly, at the same time receding the piston rod and the tool, the ratchet collar slipping by the spring retained pawls, the air or steam previously used to move the piston to a position adjacent the end 50 of the cylinder exhausts upwardly through the passage 94 and the passage 94^a through the port 105 and passage 103 and pass out through the port 106 through the passage 96, and finally through the exhaust pipe, which is connected to the passage 96. As the steam or air acts upon the piston to move it rearwardly, a small portion thereof passes up through the passage or port 99 and acts upon the auxiliary valve 100, moving the same sufficiently to cause the port of the passage 109 to register with the port 92. This registration of the passage 109 and the port 92 takes place substantially a little prior to the piston reaching the rear end of the cylinder 5. However, as soon as the registration takes place, the steam or air passes from the chamber 90 through the port 92, through the port of the passage 109, and down through the port 94^a and the passage 94 in the rear of the piston, thereby acting upon the same to push it forwardly, in which case the air or steam previously used in front of the piston is being exhausted through the passage 95, up through the port 108 through the passage 104 and through the port 107 down through the exhaust passage 96 and exhaust pipe. In this case a portion of the air or

steam passes up through the port 98 and acts upon the auxiliary valve to move it back to the position previously stated, a little before the piston reaches the forward end of the cylinder. The steam chest consists of two parts 112 and 113, bolted together and to the cylinder by means of the bolts 114. A plug 115 is threaded to the wall of the chest, by the removal of which the chamber 90 may be cleaned, or an escape of air or steam permitted, that is in case of an excess supply. Each end of the chest is provided with threaded plugs 116, to permit access to the auxiliary valve chamber.

The passages 98 and 99 extend downwardly, laterally and inclined toward each other from the chamber 91 as shown in dotted lines in Fig. 2, and open into the chamber 5^a of the cylinder 5. Where the ports 98 and 99 open into the chamber 5^a are so spaced relative to each other as indicated at 98^a in Fig. 5, so that when the piston 32 is adjacent the end 50 of the cylinder, air or steam is allowed to pass into the passage 98, and through the same to the valve chamber, behind one end of the valve, in order to operate it, in such a manner as to permit steam 90 or air to enter the chamber 5^a to operate the piston. When the piston moves from the end 50 of the cylinder 5 to the opposite end, the piston 32 uncovers the passage 99, thereby allowing exhaust steam or air to pass through the passage 99 into the valve chamber to move the valve in the opposite direction.

The invention having been set forth, what is claimed as new and useful is:—

In a rock drill; the combination of a cylinder and a piston operable in said cylinder; of a valve casing on the cylinder, provided with branch inlet ports; the valve casing near the center having an exhaust duct, and two passages extending to the ends of the cylinder chamber; a valve in the valve casing having a pair of ports, each alternately registering with the branch inlet ports, and terminating in branch ports registering with the exhaust and one of said passages, as one of the branches of the other valve port registers with the other passage; and means of communication connecting the end of the valve casing chamber and the cylinder chamber, whereby the motive medium behind the piston, when it reaches one of the ends of the cylinder chamber, will enter the valve casing and operate the valve.

In testimony whereof I have signed my name to this specification in the presence of two subscribing witnesses.

RICHARD CLAYTON FRASER.
